DESIGN FOR A RADIATOR GRILLE FOR AN AUTOMOBILE

Edmund E. Anderson, Pleasant Ridge, Mich., assignor to General Motors Corporation, Detroit, Mich., a corporation of Delaware

Application January 5, 1940, Serial No. 89,318

Term of patent 7 years

To all whom it may concern:

Be it known that I, Edmund E. Anderson, a citizen of the United States and a resident of Pleasant Ridge, county of Oakland, and State of Michigan, have invented a new, original, and ornamental Design for a Radiator Grille for an Automobile, of which the following is a specification, reference being made to the accompanying drawing forming a part thereof.

Figure 1 is a front elevational view of a radiator grille for an automobile showing my new design.

Figure 2 is a side elevational view of the grille.

Figure 3 is a section on the line 3—3 of Figure 2.

Figure 4 is a section on the line 4—4 of Figure 2.

I claim:

The ornamental design for a radiator grille for an automobile, as shown.

EDMUND E. ANDERSON.
